UNITED STATES PATENT OFFICE.

MONTAGUE REDGRAVE, OF JERSEY CITY, NEW JERSEY.

DESIGN FOR A MUSICAL INSTRUMENT.

SPECIFICATION forming part of Design No. 23,239, dated May 1, 1894.

Application filed March 23, 1894. Serial No. 504,870. Term of patent 14 years.

To all whom it may concern:

Be it known that I, MONTAGUE REDGRAVE, a citizen of the United States, residing at Jersey City, in the county of Hudson and State 5 of New Jersey, have invented and produced a new and original Design for Mouth Musical Instruments, of which the following is a specification, reference being had to the accompanying drawings, forming part thereof, in 10 which—

Figure 1 is a side elevation, and Fig. 2 is a section on the line 2, 2, of Fig. 1.

As shown in the drawings, the leading feature of my design consists in a concavo-con-

vex side *a* of circular form, a portion of its 15 periphery being cut away in the arc of a circle and having a lateral extension *a'* from one edge thereof. The outer surface of the side *a* is also shown as having two annular beads or projections *b b'* thereon. 20

What I claim as new, and desire to secure by Letters Patent, is—

The design for a mouth musical instrument substantially as herein shown and described.

MONTAGUE REDGRAVE.
